UNITED STATES PATENT OFFICE

FRANK LOUIS LYONS, OF SAN PEDRO, CALIFORNIA

LOCOMOTIVE

Application filed August 1, 1929. Serial No. 382,647.

This invention appertains to certain new and useful improvements in railway locomotives and more particularly to the novel locomotive of the steam turbine type. The 5 principal object of this invention is to provide an oil burning steam turbine driven locomotive which in use will be far more serviceable and efficient than the expandable chamber types of rolling stock now in use. 10 The various objects of the invention include the provision of novel oil and water preheating means as well as novel condensing features for the exhaust steam, these and various other objects being more thoroughly 15 apparent after a consideration of the following specification and claim.

In the drawings:

Figure 1 represents a side elevation of the entire locomotive construction. 20 Figure 2 represents an enlarged fragmentary vertical sectional view through the forward portion of the locomotive. Figure 3 represents an enlarged fragmentary vertical sectional view through the intermediate portion of the locomotive. 25

Figure 4 represents an enlarged fragmentary vertical sectional view through the rear end portion of the locomotive.

Figure 5 represents a vertical transverse 30 sectional view through the steam generating carrier of the locomotive.

Figure 6 represents a fragmentary vertical transverse sectional view through the locomotive immediately rearwardly of the 35 radiators.

Figure 7 represents a fragmentary transverse sectional view, disclosing the driving connection to the traction wheels.

Figure 8 represents a fragmentary vertical transverse sectional view, through the locomotive disclosing the connection between the 40 turbine and the drive shaft.

Figure 9 represents a vertical sectional view through a conventional type of turbine 45 such as is employed in this invention.

Figure 10 represents a longitudinal sectional view through the type of connecting rod employed.

Figure 11 represents a cross sectional view 50 through the connecting rod.

Figure 12 represents a horizontal sectional view, looking downwardly on the rear truck of the locomotive and disclosing the driving connection.

Figure 13 represents a fragmentary transverse sectional view showing the rear end portion of the oiler.

Figure 14 represents a diagrammatic view of the machine system of the locomotive.

Figure 15 represents a diagrammatic view 60 of the oil burner system.

Referring to the drawings, wherein like numerals designate like parts, it will be seen (referring to Figure 1) that the locomotive has the major portion thereof enclosed by a 65 housing 5, in the side walls of which are suitable windows 6, and the door 7. A wheeled truck generally referred to by numeral 8 supports the forward end of the vehicle, while the driving truck, generally referred to by numeral 9 supports the rear end portion of the vehicle. A standard 10 of suitable construction, extends longitudinally of the vehicle and is formed at suitable portions thereof to accommodate the aforementioned trucks. 70

Briefly, the invention includes a water and oil supplying reservoir within the rear end portion of the locomotive, at substantially the point denoted generally by the numeral 11. 80

At this end portion of the locomotive, the driving turbine denoted generally by the numeral 12 is mounted between the wheels of the trucks 9 and as shown in detail in Figure 4. The intermediate portion of the vehicle 85 includes the control means, the oil and water preheaters as well as the condenser and turbine driven generator, while the forward end portion of the vehicle, which is denoted generally by the numeral 13 (see Figure 1) includes the condenser, fire box and boiler construction. 90

The radiator structure will first be taken up and by reviewing the drawings, it will be seen that the forward end portion of the housing 5 is reduced to provide a cylindrical casing 14. 95 Extending longitudinally through the casing 14 are the air tubes 15, which open through the forward and rear end walls 16 and 17 respectively of said casing 14. The forward end of the chassis is supported by the 100

truck generally referred to by numeral 8, which includes the truck frame 18, pivotally connected as at 19 to the chassis and being provided with the usual flanged wheels 20. 5 Mounted upon the forward extremity of the chassis 10 is a post 21 for supporting an electric motor 22 and this electric motor turns the shaft which has the rear end journaled in the central portion of the front wall 16 of the 10 radiator. A fan 23 is suitably secured to the said shaft and the operation of this fan forces the air through the air tubes 15 into the compartment 24 between the housing 5 and the inner end of the radiator. This compartment 15 is provided with an outlet 25. The next phase of the invention positioned immediately rearwardly of the compartment 24 includes the refractory fire box 26. Projecting into this fire box 26 is the oil burning nozzle 27 20 and as shown in Figure 5, in each side of the fire box 8 is positioned a cylindrical water tank 28. Water tubes 29 extend upwardly from each tank 28 and converge to communicate with the boiler 30, which is of cylindrical 25 shape and positioned directly above the fire box 26. The water tubes 29 as well as the boiler 30 are confined within a compartment enclosed by the outer casing 31 and the upwardly converging inner wall 32-32, the 30 walls 32-32 being connected to corresponding side portions of the casing 31 by tie rods 33, while forward and rearward end walls 34 and 35 respectively complete the enclosure. An air admission nozzle 36 projects into the 35 fire box above the burner and a closure 37 affords access to the said fire box. Within the boiler 30 is the boiler head 38, the upper side of which is perforated as at 39 to permit the steam to enter the said head from the boiler 40. The head has an outlet pipe 40 and as clearly shown in Figure 2, a safety valve 41 communicates with the boiler 30 to permit the escape of steam when the same has reached a predetermined high pressure. The flue 42 45 permits an outlet for the fumes from the burning of oil in the fire box.

The central portion of the locomotive, which is shown in Figure 3, has provision for a seat 43, for the engineer. The numeral 44 50 denotes a cylindrical and vertically disposed water heater, while a preheater 45 also of cylindrical shape and disposed vertically serves to preheat oil. In this portion of the locomotive, a turbine 46 is provided for driving the electric generator 47, while a condenser, generally denoted by the numeral 48 55 is mounted within a compartment 49, beneath the aforementioned preheater, turbine and generator. The condenser is of usual 60 construction having the end compartments 50-50 and the water tubes extending longitudinally therethrough and indicated by the numeral 51. The release valve 52 is provided at the top of the water preheater. The rear 65 end portion of the locomotive, which has heretofore been designated by the numeral 11, includes a water reservoir 53, and an oil reservoir 54. Within the compartment 55, beneath the oil reservoir 54, are the turbines 56 and 57, one for driving forwardly and the other for driving rearwardly. These rotors each include a housing or stator 58 and the rotors 59. The rotors are suitably connected to a common drive shaft 60. Intermediate the said turbine and suitably keyed to the drive shaft 60 is a gear 61, which meshes with the laterally disposed gears 62-62 on the counter shafts 63. The gears 62-62 are in mesh with a gear 64, keyed to a drive shaft 65. Each drive shaft 65 is journaled through a supporting structure 66 and is provided at each end with a universal coupling section for connection to the universal coupling head 67 of a solid polygonally shaped bar 68, which telescopes within a hollow connecting rod 69. The ends of the rods 69 remote from the head 67 of the bar 68 is provided with means 70 for universal connection to the drive shaft 71. Each drive shaft 71 is provided with a pair of bevelled gears 72 in mesh with the bevelled gears 73 on the traction wheels 74 of the rear track, which has been generally referred to by numeral 9. Obviously by cutting out one of the turbines, the locomotive will be driven forwardly and by cutting down that turbine and admitting steam to the other turbine, the locomotive may be driven rearwardly with the usual power. As clearly shown in Figure 8, the hood 75 projecting laterally from the housing 5 serves to protect the gearing. 70

Reference to the diagrammatic view shown in Figure 14 will now be made, in which figure the water supply tank 53 is shown connected by means of the pipe 76 to one end of the condenser 48. The water passes through the condenser and through the pipe 77 and is forced by means of the pump 78 into the preheater 44. The water is herein preheated by exhaust steam and is delivered through the pipe 79 to the boiler, hereinbefore denoted by the numeral 30, the live steam issuing from the head 38 within the boiler travels through the pipe 80 to the turbine 46, through a valve 81, a branch pipe 82 connects the pipe line 80 with the driving turbine 57 while a branch pipe 83 communicates the steam line 80 with the driving turbine 56, through a control valve 84. The exhaust pipes 85 and 86 from the turbines 57 and 56 respectively connecting with the exhaust lines 87 connect with the preheater 44, for preheating the feed water travelling therethrough. The exhaust gas travels from the preheater to the condenser 48 through the pipe line 88, and a suction pump 89 communicates with the condenser in the manner as clearly shown. The steam entering the condenser escapes from the condenser through the pipe 90 and is forced by the pump 91 into the water compartment 75 of the radiator 14. The exhaust from the 80 85 90 95 100 105 110 115 120 125 130

turbine 46 enters the preheater 45 and escapes from there by way of the tube 92 into the water preheater 44.

The oil burner system will now be described, and this (referring to Figure 15) includes the pump 93 for forcing the oil from the tank 54 by way of the pipe 94 and through the pipe 95 into the oil preheater 45. After the oil is heated, the same travels through the pipe line 96 and through the valve 97 to the burner before denoted by numeral 27.

In Figure 3 it will be seen that a pair of control levers are denoted by the numerals 98 and 99. These levers are pivotally mounted and are connected by means of the rod 100 to the valve 84 and 101. The valve 101 serves to completely shut off the steam to the turbines 56 and 57, while the valve 84 serves to cut off the steam to the turbine 56, when it is desired that the locomotive move forwardly or vice versa, depending upon the arrangement of the turbine. The pull cord 102 is trained over a pulley 103 and connects to the release valve 52.

It will thus be seen that the novel locomotive may, because of its oil burning character be cleaned and may be attractively finished in colors, if desired, and because of the novel water and oil preheating features, the invention will be far more efficient and practical for the purpose stated than locomotives of this nature heretofore devised.

While the foregoing specification sets forth the invention in detail, it is to be understood that numerous changes in the specific shape, size and materials may be resorted to, without departing from the spirit and scope of the invention as hereinafter claimed.

What is claimed as new is:

A drive connection for a locomotive comprising front and rear wheeled trucks, a pair of oppositely acting turbines between said trucks, a turbine shaft common to both turbines, a gear on said turbine shaft, driven shafts on opposite sides of the truck and geared to the wheels of the said truck, a stub shaft between adjacent ends of corresponding driven shafts of the said front and rear truck respectively, a slide coupling connecting each end of a stub shaft with the said adjacent ends of the said corresponding drive shaft, a gear on each stub shaft, and connecting gearing between each stub shaft gear and the turbine shaft gear.

In testimony whereof I affix my signature.
FRANK LOUIS LYONS.
